UNITED STATES PATENT OFFICE

MAURICE ALLAND, OF ATLANTIC CITY, NEW JERSEY

UMBRELLA AND PARASOL

Application filed June 18, 1929. Serial No. 371,759.

The object has been to provide improvements in umbrellas and parasols broadly, but more specifically in the handle structure, and its relation to the ribs which support the cover.

Numerous attempts have been made to provide in an umbrella or parasol a suitable means for holding the free end portions of the ribs in close proximity to the handle 10 when the device is in closed position, but the fact that few if any of those heretofore devised have come into use to any great extent or for any extended length of time indicates that they have not proved to be an entire 15 success.

Furthermore, in conformity with various developments in feminine styles, there has developed a need for a device for not only retaining the free ends of the ribs in closed 20 position, but one which is also operable to maintain in such ends a uniformly partially extended position, so that when the umbrella or parasol is on display, or when it is closed and is being used during a stroll, the appearance of the same is greatly enhanced 25 over that which it presents when either closed but loosely, or when the rib ends are bound tightly against the staff.

An object of the invention therefore has 30 been to provide a construction in which these highly desirable features are embodied, and at the same time one which is inexpensive to manufacture, is not readily liable to become disarranged or out of order, and 35 which is most efficient in the performance of its function.

With these and other objects in mind, the present invention comprises further details of construction and operation which are 40 fully brought out in the following description when read in conjunction with the accompanying drawings in which Fig. 1 is a side elevation of a parasol in which one form of the invention is embodied, the same 45 being shown partly in section; Fig. 2 is an enlarged section of the sectioned portion of Fig. 1 but in a different position; and Fig. 3 is a sectional view similar to Fig. 2, but illustrating a modified form of the invention.

Referring to Figs. 1 and 2, an umbrella or

parasol is shown as comprising a staff 1, carrying a ferrule 2, from which protrudes a threaded stud 3. To this stud is secured in threaded engagement a staff extension element 4, provided upon its outer surface with suitable relatively coarse and preferably square threads, beyond which the free end portion of said element is reduced and threaded at 5 to receive and operatively connect with said staff a handle 6 of any suitable size, shape and material.

Rotatably mounted upon the threaded element 4 is a transversely extending partition 7, having a threaded aperture 8, through which said element extends, said partition 65 extending transversely of and closing one end of a cylindrical member 9, which spirally receives in telescopic association the adjacent end portion of the handle 6. Upon the opposite side of said partition to said member, said partition is preferably integrally connected with a radially outwardly flaring disc or skirt 10, which terminates at its periphery in a preferably cylindrical flange 11.

Said disc or skirt 10 is provided inwardly with a substantially unbroken or regular conical surface 12, which radially outwardly is provided with a circumferentially extending groove 14, preferably adjacent to the flange 11.

In the operation of this device, the partitioned element 9 is adjusted upon the threaded staff extension 4 so that the free end portions 15 of the usual ribs 16 enter and are retained against radial dislodgment within the groove 14, the fabric of the umbrella or parasol cover 17 being free to hang loosely outwardly in uniform relation about the staff 1, substantially as shown in Fig. 1.

If a different or more closed arrangement of the ribs and cover is desired, the element 9 is rotated upon the staff extension 4 sufficiently to release the rib ends 15 from within the groove 14, so that said ribs may be contracted into engagement with the conical surface 12 of the disc or skirt 10. Immediately thereafter the element 9 may be rotated in the reverse direction, thereby forcing said ribs to be contracted radially inwardly to 100

wards and closely about the staff 1, until the ends 15 are received within and retained by the radially outer limits of the concaved recess 13. It will also be noted that in this 5 form of the device, the element 9 when longitudinally withdrawn upon said staff extension slides over the adjacent end of the handle 6, and when it slides in the opposite direction upon said extension is arrested in 10 movement before its leaves the proximity of said handle, so that there is at no time a gap between said element and said handle, as shown in Fig. 2.

Referring to Fig. 3, the modified embodiment is shown as comprising an umbrella or 15 parasol represented by a staff 20, surrounded by ribs 21, to which is secured the usual fabric 22, said ribs having the well-known type of enlarged terminal portions 23. Into 20 the free end portion of said staff 20 is permanently secured in any suitable manner the reduced end portion 24 of an extension member 25, the outer surface of which is provided with relatively coarse square 25 threads, beyond which said member is reduced at 26 and permanently secured in any suitable manner into a handle 27, which may be of any size, shape, or material.

Rotatably mounted upon the threaded surface of the extension member 25 is the transversely extending partition 28 of a cylindrical member 29, which in one extreme position moves telescopically over the adjacent portion of the handle 27, while in its other position its longitudinal movement is limited 35 when it forms a substantial continuation of the surface of said handle, but without leaving an appreciable gap between them. From the opposite side of the partition 28, the member 29 merges into a preferably cylindrical flange 30, which, as shown in Fig. 3, 40 operates to receive, surround and secure the termini 23 of the ribs 21, to prevent said ribs from moving radially outwardly and the umbrella opening when such is not desired. The outer surfaces of both of the 45 cylindrical members 9 and 29, hereinbefore described, may be provided with finger-engaging irregularities 31 of any suitable 50 spacing, shape and arrangement.

Having thus described my invention, what I claim and desire to secure by Letters Patent of the United States is:—

1. An umbrella including a staff having 55 ribs and handle attached, in combination with an element slidable upon said staff with respect to said ribs, and operative to retain the ends of said ribs either in a contracted or in a partially extended relation.

2. An umbrella including a staff having 60 ribs and handle attached, in combination with an element slidable upon said staff and overhanging said handle, said element being 65 provided with means operative to retain the

ends of the ribs either in a contracted or in a partially extended relation.

3. An umbrella including a staff having ribs and handle attached, in combination with an element slidable upon said staff and overhanging said handle, said element being provided with a radially inwardly positioned recess and with a radially outwardly positioned peripheral groove, either said recess or said groove being adapted to receive and retain the ends of the ribs in fully closed or partially open position, selectively. 70 75

4. An umbrella including a staff having ribs and handle attached, in combination with an element slidable upon said staff and overhanging said handle, said element being provided with a radially inwardly positioned recess and with a radially outwardly positioned peripheral groove connected by a substantially conical surface, said groove being adapted to receive and retain the ends of said ribs in partially open position, and when released from said groove said ribs in engagement with said surface being forced radially inwardly towards said recess, as said element is moved longitudinally toward said rib ends upon said staff. 80 85 90

5. An umbrella including a staff having ribs and handle attached, in combination with a disc having a conical surface and movable longitudinally upon said staff, said surface being engageable with the rib ends and operative to propel them radially inwardly towards closed position. 95 100

6. An umbrella including a staff having ribs and handle attached, in combination with a disc having a conical surface and movable longitudinally upon said staff, said surface upon engaging the rib ends operating to propel them radially inwardly towards closed position, and said surface merging radially outwardly into a peripheral groove adapted to receive and operative to then retain said rib ends in partially open position. 105 110

In testimony whereof I have affixed my signature.

MAURICE ALLAND.
